UNITED STATES PATENT OFFICE.

EMILY JONES, OF BROOKLYN, NEW YORK.

SCISSORS SHARPENER.

Application filed March 16, 1922. Serial No. 544,204.

To all whom it may concern:

Be it known that I, EMILY JONES, a citizen of the United States, and a resident of the city of New York, borough of Brooklyn, in the county of Kings and State of New York, have invented new and useful Improvements in Scissors Sharpeners, of which the following is a full, clear, and exact description.

10 This invention relates to scissors sharpeners.

The general object of the invention is to provide a simple, efficient and durable scissors sharpener, which device presents a neat 15 and attractive appearance and of such a size that it may be carried in work boxes and the like.

A further object is the provision of a scissors sharpener adapted for use with all 20 sizes of scissors and that may be operated by people who have little mechanical skill.

These objects are accomplished by providing an instrument cast from glass, the handle of which is cylindrical and provided 25 with a plurality of circumferential grooves, the head of which has a plurality of curved faces of different thicknesses formed thereon, each face being provided with a plurality of grooves.

30 These and other objects of the invention will be more clearly understood from the following detailed description and accompanying drawings, in which—

Figure 1 is a plan view of the scissors 35 sharpener;

Figure 2 is a section along the line 2—2, Figure 1; and

Figure 3 is a section along the line 3—3, 40 Figure 1.

Referring to the above mentioned drawings, a handle 10 is shown which is of smaller diameter at the upper end than at the lower end. A plurality of grooves 45 11 and 12 are formed in conjunction with the handle at the bottom and top, respectively. Attached to the upper end of the cylindrical handle 10 is a head 13. Three curved faces 14, 15 and 16 of different thicknesses are formed on the head 13. A plurality of grooves 17, 18 and 19 are formed in the faces 14, 15 and 16, respectively. These grooves are varied in size, depending on the

thickness of the face in which they are formed. In order to accommodate scissors of different sizes the faces are made of different thicknesses and the size of the grooves is decreased with the thickness of the face. Projections 20 are formed on the handle to provide a means for gripping the same. An opening 21 extends through the head 13 and serves as a means for hanging the scissors sharpener up when not in use.

The scissors sharpener may be made from a variety of materials that are harder than the steel used in scissors. It has been found that the preferable material for the construction of such a device is glass of a fairly hard quality which is usually harder than the steel used in the construction of scissors.

From the foregoing it will appear that a scissors sharpener has been devised which is simple to operate and compact in size. It may be made of a variety of designs which will appear attractive to nearly any individual.

In operating the device, all that is necessary is to grip the blades of the scissors in the grooves and by closing and releasing the handle the device may be operated.

I would state in conclusion that while the illustrated example constitutes a practical embodiment of my invention I do not limit myself strictly to the exact details herein illustrated since manifestly the same 85 can be considerably varied without departing from the spirit of the invention as defined in the appended claim.

Claim—

As a new article of manufacture, a scissors sharpener of the character described, comprising a tapering cylindrical handle, a plurality of circumferential ridges formed integral with the handle at each end, said circumferential ridges being spaced apart forming circumferential grooves, a head having an opening therethrough formed integral with the smaller end of the handle, and a plurality of curved faces of different thicknesses formed on the head, each curved face having a plurality of grooves formed therein.

EMILY JONES.
